UNITED STATES PATENT OFFICE.

HENRY F. BECHMAN, OF BATTLE CREEK, MICHIGAN, ASSIGNOR TO THE DUPLEX PRINTING PRESS COMPANY, OF SAME PLACE.

PRINTING-PRESS.

SPECIFICATION forming part of Letters Patent No. 643,999, dated February 20, 1900.

Application filed June 8, 1898. Serial No. 594,714. (No model.)

To all whom it may concern:

Be it known that I, HENRY F. BECHMAN, of Battle Creek, in the county of Calhoun and State of Michigan, have invented certain new 5 and useful Improvements in Printing-Presses; and I do hereby declare that the following is a full, clear, and exact description thereof, reference being had to the accompanying drawings, and to the letters of reference marked 10 thereon, which form part of this specification.

This invention is an improvement in movable bed and cylinder web-printing presses.

The object of this invention is to shorten the travel or stroke of the cylinder in that 15 class of flat-bed printing-presses in which locomotive or reciprocating cylinders are employed, and thus reduce the necessary length of the machine and increase its speed, or, retaining same length of stroke, it admits the 20 use of additional form-rollers, which improves the quality of the work, and also gives more time between impressions in which to shift the web, thus materially contributing to speed.

The invention is particularly useful as applied to flat-bed presses such as is described 25 in the patent to Cox, No. 478,503, dated July 5, 1892. In that class of presses the reciprocation of the bed during impression, while the impression-cylinder is coacting with the 30 forms, in itself, materially reduces the stroke of the machine and correspondingly increases its speed. Nevertheless, as this movement of the bed necessitates a corresponding movement of the web, which does not take 35 place when the beds are stationary, the difficulties involved in providing for this movement of the web with movable beds are so great that practically no advantage is gained. My invention hereinafter described obviates 40 entirely these difficulties, inasmuch as by my devices the web is not held stationary relative to the frame of the machine during the act of impression, as the whole of that portion of the web within the press and over the 45 beds is carried back and forth with the beds. This enables me to obtain all the advantages derivable from moving the bed oppositely to the movement of the cylinder, and thus shorten the travel of the latter without incurring the 50 great disadvantages involved in securing the

proper movement of the web in constructions heretofore known. In short in my invention I bodily move the beds and the web-guide rollers at each end of the beds just as if the beds and web-guiding mechanism in the aforesaid Cox 55 patent from one looping-roller back to the other were pulled back and forth while the cylinders travel—that is, the entire system of guide-rollers whereby the web is presented to the beds and reversed are immovable in 60 relation to the beds, but travel therewith in my press, just as they are stationary in relation to the beds in said Cox patent. This will be more fully explained hereinafter.

An additional object of the invention is to 65 cause the reciprocating cylinder to move the bed in the opposite direction by the peculiar system of gears and racks hereinafter described.

The invention therefore consists in the combinations and constructions of mechanisms and parts thereof summarized in claims, and the best form of press now known to me is illustrated in the accompanying drawings, in which— 70

Figure 1 is a longitudinal vertical section of the press with the inking mechanism removed. Fig. 2 is a transverse vertical section on line 2 2, Fig. 1. Fig. 3 is a transverse vertical section on line 3 3, Fig. 1. Fig. 4 is 80 a detail front end elevation of press. Fig. 5 is a detail of the gearing between the cylinder and bed and frame. 75

The movable type-beds A A' are arranged parallel, one over the other, and suitably supported on guides a a', attached to the main frames Y. Coacting with said beds are cylinders B B', journaled in cross-heads C, supported and guided on the frames Y, said cross-heads being connected by pitmen C' to 85 crank-pins d on large crank gear-wheels D on the main shaft D' at the rear end of the machine, which is driven by a pinion e on the power-shaft E, as in the Cox presses. On shafts b' of cylinders B B' are keyed pinions F F', which mesh with stationary racks f f', fastened to the side frames Y. On said shafts are also secured gears G G' of same diameter as the impression-cylinders and meshing with racks g g', attached to the type- 95 100

beds A A'. Therefore when the cylinders are moved in one direction the beds are moved in the opposite direction, or vice versa.

At each side of each impression-cylinder, 5 above the type-bed and journaled in the cross-heads C, are web-guide rollers H h H' h'.

Mounted upon horizontal extensions Y of the side frames, at the front end of the press, are reciprocating castings I, in which are journaled a lower web-guide roller i and an upper web-guide roller i'. The castings I are connected to the upper bed A' by rods I', so that they move synchronously with said bed.

J and j are parallel rock-shafts journaled 15 in the side frames adjoining the rear ends of the beds, the lower rock-shaft J having depending arms J', in which is journaled a web-guide roller J², and shaft j, having upstanding arms j', in which is journaled a web-guide roller j². On the outer ends of shafts J and j are toothed segments J³ and j³, respectively, which intermesh, so that the shafts are rocked synchronously, so as to swing the guide-rollers simultaneously forward or backward. The shafts are rocked 25 by rods J⁴, which connect arms J' to extensions A² on the upper bed, as shown, the connection being such that rollers J² and j² will have a lateral movement equal to the end-wise motion of the bed.

Beside but in rear of shaft J is a guide K⁵, and in rear of shaft j is a guide k⁵, and just in rear of these guides are a pair of equalizing looping-rollers l l', journaled in vertically-movable bars L, having cam-rollers L' on their lower ends engaging a cam-race M' in disks M, attached to a shaft M², driven by a gear M³ from one of the crank-wheels D, as shown.

40 In rear of the equalizers is a pair of feed-cylinders N N' and coacting tapes n, running over guide-rollers n', as shown, said feed-cylinders being intergeared and driven by a train of gears N² N³ from main shaft D'.

45 Above the equalizers is a delivery-cylinder O and coacting tapes o, running over rollers o', as shown, the cylinder O being driven from shaft D' or the feed-cylinders by a train of gearing (not shown, but fully disclosed in 50 said Cox's patents) and at substantially-uniform speed with the feed-cylinders.

The feeding-cylinders and delivery-rolls and the equalizing or looping rollers are constructed and operate in substantially the 55 same manner as in the aforesaid Cox's patent.

The web W is led in from a roll W' under a guide-roller w, up over cylinder N, down under cylinder N', up over lower looping-roller l, down between guide k⁵ and shaft J, down 60 under roller J², thence over roller H, under cylinder B, up over roller h forward to and under roller i, up to and over roller i', back to roller h', then under cylinder B', up over roller H', back to roller j², down between 65 guide k⁵ and shaft j to and under upper looping-roller l', then up to the delivery O o, as shown.

The shafts J and j may be provided with projections J⁵ and j⁵ to prevent the web sagging against the shaft and keep it close to 70 guides K⁵ k⁵.

The operation is as follows: The cross-heads C, moving back and forth, carrying the impression-cylinders B and B' with them, cause said cylinders to revolve by means of 75 gears F and F', Figs. 1 and 2, and stationary racks f and f'. The peripheral speed of gears G G', &c., and also printing-surface of cylinders B and B', is consequently greater than peripheral speed of gears F and F'. This causes 80 racks g g', with attached beds A A', to have a motion relative to main frames Y opposite in direction to that of cross-heads C. The speed of and distance traveled by beds A A' depends upon the ratio of diameters between 85 gears G F and G' F'. Rollers l l' are given such a motion by cam M as to hold the web of paper being printed upon stationary during the printing operation relative to guides K⁵ k⁵ and at the same time take up surplus paper 90 being fed in by feed-cylinders N and N' and to give out surplus paper to the delivery O, just as they operate in the aforesaid Cox patent. Said rollers l l' also shift the web forward over the beds when the cylinders are at 95 and near ends of travel, so that blank portions of paper are brought into proper position 100 relative to the type for printing a new sheet, as described in the said Cox patent. Rolls J² j² i i' are moved exactly with the moving 105 beds A A', so as to bodily move that portion of the web of paper being printed upon with said beds A A', thus preventing any sagging or breaking of the web in whatever direction the beds may be moving. As the cylinders 110 move to the right the beds move to the left. Consequently rollers i i' and J² j² move to the left also; and when the cylinders move to the left the beds move to the right, and said rollers move with the beds to the right also. 115 Obviously if the beds move during printing the web must move bodily with the beds or be ruptured. Moving said rollers with the beds avoids this. For instance, if the beds move to the left five inches rollers i i', moving five 120 inches to the left with the beds, feed the web to the beds or allow the web to move back with the beds, preventing any strain on the web, and rollers J² j², moving to the left, move back that part of the web to the left of the cylinders 125 and beds and take up the slack in web which would be formed by the left movement of the beds if the rollers did not compensate therefor. On the movements of the beds to the right the swinging rollers J² j² yield, so as to 130 allow the web to be moved with the beds to the right and rollers i i' take up the slack that would be otherwise formed by such movement of the beds. Thus the rollers J², i, i', and j² are wholly independent, so far as 135 their web-looping compensating functions are concerned, of the looping-rollers l l', which act simply as they do or would do if the beds were stationary.

Having thus described my invention, what I claim as new, and desire to secure by Letters Patent thereon, is—

1. In a printing-press, the combination of a traveling impression-cylinder, an oppositely-movable type-bed, a rack on the bed and a rack fixed on the frame; with a pair of gear-wheels of unequal diameter attached to the cylinder and respectively working in the rack fixed to the frame, and in the rack on the bed of the press whereby as the cylinder is traveling in one direction the bed is moved in the opposite direction, substantially as and for the purpose set forth. 5
  2. In a printing-press, the combination of a traveling cylinder, and oppositely-moving bed, and a pair of gear-wheels of unequal diameter attached to the traveling impression-cylinder, and means for reciprocating said cylinder; with a stationary rack on the frame of the press; and a rack on the bed; the smaller of the two gear-wheels working in the rack fixed to the frame of the press, and the larger gear-wheel working in the rack fixed 10 to the movable type-bed of the press, substantially as and for the purpose set forth. 20
  3. In a printing-press, the combination of a pair of movable type-beds, a rack on each bed; and a fixed rack on the frame beside each bed; with a pair of locomotive impression-cylinders each having a pair of gear-wheels of unequal diameter fixed thereon, the members of each pair of gears respectively working in a rack on the frame and in a rack 25 on the coöperating type-bed and means for simultaneously reciprocating said cylinders, substantially as and for the purpose set forth. 30
  4. In a printing-press, the combination of a pair of locomotive impression-cylinders, a pair of movable type-beds, and web feeding and delivering mechanisms, with a pair of web-carrying rollers journaled in swinging arms or brackets provided with intermeshing segments, one of said arms being directly 35 connected to and reciprocated by the beds, substantially as and for the purpose set forth. 40
  5. In a printing-press the combination of a movable type-bed, an oppositely-movable cylinder, web feeding and delivery mechanism, a pair of equalizing looping-rollers adapted to assist in shifting the web intermittently over the bed, a pair of rollers journaled in oscillating arms and suitably connected so as 45 to oscillate together, and operated directly from the beds substantially as described; 55 with a web-carrying roller at the opposite end of the bed beyond the range of travel of the cylinder and movable by and with the bed, all substantially as described.
  6. In a perfecting-press, the combination of the beds and cylinders, the web feeding and delivery mechanism, substantially as described; and movable guide-rollers between the beds; with a swinging guide-roller between the feed and first bed, a similar swinging 60 guide-roller between the second bed and delivery said swinging rollers being mounted on rock-arms, intermeshing segments on said arms, and a pitman connection between one rock-arm and the beds, substantially as described. 65
  7. In a printing-press, the combination of a pair of locomotive impression-cylinders, a pair of movable type-beds and web feeding and delivery mechanism, with a pair of web-carrying rollers attached to the beds and a pair of web-carrying rollers journaled in swinging arms or brackets, intermeshing segmental gears on said arms, and connections 70 between said arms and the beds substantially as and for the purpose set forth. 75
  8. The herein-described perfecting-press, consisting of the upper and lower beds, and means for moving them simultaneously in the same direction; the upper and lower cylinders and means for moving them simultaneously in the same direction but opposite to the beds; the pair of guide-rollers intermediate the cylinders attached to and moving with the beds; a continuous web-feed mechanism, 80 a continuous web-delivery mechanism, a pair of connected looping-rollers for converting the continuous feed and delivery of the web into an intermittent movement over the beds; and a pair of swinging looping-rollers connected to and moved by the beds, between the beds and looping mechanism, all substantially as and for the purpose described. 85
- In testimony that I claim the foregoing as my own I affix my signature in presence of two witnesses. 90
